BUBBLE BLOWING WAND

Louis J. Ziff, Philadelphia, Pa., assignor to Larami
Corporation, Philadelphia, Pa.

Filed Dec. 26, 1972, Ser. No. 318,688

Term of patent 14 years

Int. Cl. D21—01

U.S. Cl. D34—15 H

FIG. 2

FIG. 3

FIG. 1 is a perspective view of a bubble blowing wand showing my new design;

FIG. 2 is a top plan view thereof, the side opposite being identical;

FIG. 3 is a side elevational view thereof, the side opposite being identical;

FIG. 4 is a right end elevational view thereof;

FIG. 5 is a left end elevational view thereof.

I claim:

The ornamental design for a bubble blowing wand, as shown and described.
